UNITED STATES PATENT OFFICE.

JOSEPH ANTON DEMPF, OF WASHINGTON, DISTRICT OF COLUMBIA.

CIRCUIT-CLOSER.

SPECIFICATION forming part of Letters Patent No. 424,182, dated March 25, 1890.

Application filed January 9, 1890. Serial No. 336,445. (No model.)

To all whom it may concern:

Be it known that I, JOSEPH ANTON DEMPF, of Washington city, in the District of Columbia, have invented a new and useful Improvement 5 in Circuit-Closers for Electric Bells, &c., of which the following is a specification.

The object of my invention is to provide a circuit-closer or set of electrical contacts designed especially for electric bells, but applicable also to other uses, which shall permit of the closing of an electric circuit by pulling on a suspended tassel in contradistinction to pressing upon a push-button.

It consists in the peculiar construction and 15 arrangement of parts, which I will now proceed to describe with reference to the drawings, in which—

Figure 1 is a view of the device applied to a suspended tassel and cord, and Fig. 2 is an 20 enlarged sectional view.

A represents a non-conducting block of wood or similar material, having a flange *a* at its upper end and a bulbous projection *b* at its lower end. This block is bored out 25 with three different diameters, the largest at the top and the smallest at the bottom. At the bottom of the upper and largest bore are placed two detached segments *B B'* of a circular metal ring, which segments are insulated 30 from each other and form the terminal contact-plates of the two circuit-wires *b' b*.

C is a hollow metal stem having a disk or plate *c* at its upper end, which fits the largest or upper bore of the block, and the stem of 35 which disk extends through the smallest and lowest bore to a position below the bulbous end of the block.

D is a spiral spring coiled around the stem C and bearing at its upper end against 40 the disk *c* and at its lower end against a plate *d* in the bottom of the intermediate bore of the block. The function of this spring is to normally hold the disk *c* up and away 45 from contact with the segmental plates *B B'*, and to yield when the stem is pulled downwardly, and by bridging the break between these plates to close the circuit through the wires. The terminal plates *B B'* may be of other shape than segmental, and may also be 50 constructed as springs or yielding contacts.

In applying the circuit-closer to electric-bell

circuits, the flange of the block A is screwed up against the ceiling, and the pull-cord and tassel are connected to the hollow stem C. The device may, however, be used in other 55 positions.

I am aware that it is not broadly new to close contact in an electric circuit by a vertical spring-seated stem arranged to be pulled downwardly by a cord, as shown, for instance, in Patent No. 368,512. My invention is, however, marked by the following peculiarities: There is no independent insulating bushing for the rod to play in and be guided by; but the rod C in my case has its 65 disk *c* at the upper end fitting the larger bore of the block and guided thereby, and forming also the conductor for connecting the two terminals *B B'*, which are located at the bottom of the larger bore. To stop the 70 upward movement of the disk *c*, a bridge-plate or diametrical cross-piece *p* is fastened to the block directly across the chamber. By making the stem C hollow, also, the cord may be inserted into the same in connecting it 75 thereto, so as to avoid an unsightly knot, and also the fraying or cutting of the cord.

Having thus described my invention, what I claim as new is—

The combination, with the block A, bored 80 or chambered with three different diameters, the largest being at the top and the smallest at the bottom, of the two terminals *B B'*, placed at the bottom of the largest diameter, the stem C, passing through the smallest diameter and having a disk *c* fitting the largest diameter, a spiral spring wound about the stem and having its lower end bearing against the bottom of the middle bore and its upper end against the disk *c*, and a bridge-plate or 85 stop *p*, arranged across the top of the largest bore or chamber to limit the upward movement of the disk, substantially as shown and described.

The above specification of my invention 90 signed by me in the presence of two subscribing witnesses.

JOSEPH ANTON DEMPF.
